INVENTOR

By his Attorney William H. Kenyon

UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 13,798, dated March 20, 1883.

Application filed February 14, 1883. Term of patent 3½ years.

To all whom it may concern:

Be it known that I, WINTHROP L. JACOBS, of East Orange, Essex county, New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The ground is closely filled in with running

geometric figures and small leaf-like forms variously and irregularly connected. Disposed loosely over this ground is a system of radially-arranged figures interspersed with plant-like figures, entirely unconnected with each other, as is shown in the photograph.

I claim—

The design for a carpet, consisting of the design substantially as shown and described.

WINTHROP L. JACOBS.
